TOBACCO-MANIPULATING MACHINES

Raymond Lanore, Paris, France, assignor to Usines Decoufle S.A., Paris, France, a French company
Original application Dec. 16, 1957, Ser. No. 702,905, now Patent No. 3,032,041, dated May 1, 1962. Divided and this application Nov. 27, 1961, Ser. No. 155,149
Claims priority, application France, Jan. 10, 1957,

1 Claim. (Cl. 131—61)

This application is a division of my co-pending application Serial No. 702,905, filed December 16, 1957, now Patent No. 3,032,041, granted May 1, 1962, which claims an apparatus by which the method of the instant application may be practiced.

This invention relates to an improved method of forming a tobacco filler, for example in a continuous rod cigarette-making machine.

It is sometimes desired to form a tobacco filler in which the tobacco is denser at parts where it is to be cut than at other parts along its length, in order that the tobacco articles formed by cutting the filler may be more densely filled with tobacco at their end portions than at other parts. It is usual to form a tobacco filler from a relatively loose stream of tobacco, sometimes called a tobacco rod, which is compressed laterally so as to give it a reduced and uniform cross-sectional size. Thus if there is more tobacco at some parts of the stream than at others, the compressed filler will have corresponding parts of greater and less density, and accordingly, one known way of forming such a filler is to add increments of tobacco at suitable intervals along the stream.

The present invention provides a method of producing a tobacco filler in which the tobacco is denser at parts where it is to be cut than at other parts along its length, which method comprises forming a tobacco stream which contains an excess of tobacco, and trimming the stream by removing tobacco bodily therefrom while leaving a greater quantity of tobacco per unit length at regularly spaced positions along the stream and a smaller quantity per unit length between the said positions. The trimming of the stream may be effected in such a way as to reduce the stream to a smaller cross-sectional size between the said positions than at the said positions, the tobacco at the said positions being then made denser than the tobacco between the said positions by subsequently laterally compressing the trimmed stream to a uniform cross-section.

The method according to the invention may be practiced with the aid of apparatus for forming a continuous tobacco filler in a cigarette-making machine, and one such apparatus will now be described by way of example with reference to the accompanying drawings, in which:

FIGURE 1 is a diagrammatic longitudinal section showing the upper or feed portion of a cigarette-making machine in which a tobacco filler is formed;

FIGURE 2 is a longitudinal section showing diagrammatically, on a larger scale, a stream of tobacco as originally formed in the machine shown in FIGURE 1;

FIGURE 3 is a plan view of a trimming device and includes guide means shown in section, for trimmed tobacco, and

FIGURE 4 is a vertical section taken upon the line IV—IV, of FIGURE 3, the guide means being omitted.

Referring to FIGURE 1, tobacco is fed by a distributor 1 onto an endless belt conveyor 2 between the transverse walls 3, 4 of a discharge hopper. The stream of tobacco travels on the band 2 toward the cigarette-rod-forming mechanism.

The stream of tobacco as formed on the conveyor 2 is uneven in height, being characterized by alternating

2

troughs and crests, and its longitudinal section is shown diagrammatically in FIGURE 2, in which the unevenness of its height is considerably exaggerated.

The stream of tobacco contains more tobacco than required for making cigarettes having a desired average weight, and the excess tobacco is trimmed at the location indicated by the reference numeral 5. This trimming step consists in separating and moving away from the stream any tobacco above the level *h* (FIGURE 2), in those portions of the stream where it is desired to have a normal density of the filler, and above the level *hl* in the portions where a greater tobacco density is desired. These last-mentioned portions are normally spaced from one another by a distance *l* (FIGURE 2) equal to the length of one cigarette, so that in each cigarette the tobacco may be denser at one or both ends, depending on the location of the cut where each cigarette leaves the rod from which it was formed. However, if it is desired to increase the density of the tobacco at only one end of the cigarette, the thicker portions may be spaced apart by a distance equal to two cigarette lengths.

As a rule, the high-density portions have a density 10% higher than the normal density of the other portions of the roll. The length of these thicker portions is usually about $\frac{3}{8}$ ".

In the embodiment described herein, the height *h* is about $\frac{3}{4}$ " and therefore the height *hl* is about or nearly $\frac{7}{8}$ ".

The stream of tobacco is carried along by the travelling band 2 moving in a horizontal channel 6, FIGURES 3 and 4, and having its edges 7 guided and held by side plates 8. The initial portion of this channel is tapered to compress the tobacco therein, and the next portion has its edges parallel and spaced about $\frac{5}{16}$ " apart in the trimming zone. The trimming device for separating and discharging the excess tobacco comprises two horizontal rotary discs 9, having chamfered edges, and rotating in opposite directions as shown by the arrows in FIGURE 3. The linear velocity of the outer edges of these discs is about 15% greater than the linear velocity of the stream of tobacco. These outer edges, although shown in the drawings as apparently in contact, are separated at their nearest points by a gap which may be between .004" and .008". A cylindrical rotary brush 10, about $\frac{1}{4}$ " thick, overlies the discs 9 and is mounted at one end of a shaft 11 rotatably driven at high speed and set at an angle with respect to the direction of flow of the tobacco, as shown. This brush is positioned in the zone where the discs are nearest to each other and brushes against the upper surfaces of the discs at that zone, thereby engaging and removing surplus tobacco which is above the discs and completing the separation of that tobacco from the tobacco beneath the discs. The tobacco thus removed is driven by the brush 10 between the walls 12 and 13 which guide it onto a travelling band (not shown) by which the excess tobacco is returned to the distributor.

The discs 9 rotate once for every four cigarettes produced. The outer peripheral parts of the discs are not uniformly level but are formed with four raised portions 14, whose under-surfaces are recessed as shown in FIGURE 4. They are spaced 90° apart and have raised edges situated .08" above the level of the remaining portions of the discs therebetween. The two discs are so disposed that as they rotate, successive pairs of raised portions 14 register with one another as shown in FIGURE 3. These raised portions are bounded by straight edges 19 set at suitable angles relative to radii terminating at the outer peripheral edges of the disc. These angles are suitably chosen so that when two raised or recessed portions 14 register with each other, their leading edges are momentarily in line with each other as shown in FIGURE 3.

The raised or recessed portions 14 thus pass over the

stream of tobacco at intervals each corresponding to one cigarette-length. Moreover, when two portions 14 register with each other on the line IV—IV of FIGURE 3 they are directed as shown with their leading edges substantially parallel to the plane of the rotary brush 10. Since the discs 9, with their recessed portions 14, cooperate to determine the depth to which the stream is trimmed, and since the edges of the portions 14 are at a greater distance from the lower part of the band 2 than are the edges of the other parts of the discs, it will be seen that the recessed portions 14 allow the stream to retain a greater depth of tobacco than do the remaining parts of the discs.

This brush 10 is so adjusted as to be substantially flush with the lower portions of the upper faces of the discs 9. When the raised portions 14 move beneath the brush 10, the bristles of the brush are slightly bent, see FIGURE 4, and the excess tobacco is removed from these raised portions without difficulty.

Thus the stream of tobacco in its subsequent travel on the band 2 has, at desired spaced intervals, portions containing a greater quantity of tobacco than the remaining zones located therebetween.

This stream of tobacco is subsequently caused to pass under a wheel 15 which compresses it laterally and forms a tobacco filler of uniform cross-sectional size in which the tobacco at the said desired portions is denser than at others.

This stream is then delivered onto a paper web 16 passing over a small roller 17 onto an endless band 18 by which the paper web supporting the filler of tobacco is carried along through the actual rod-forming mechanism. The cigarette rod so formed is then separated into individual cigarettes by cutting through or adjacent to the denser portions, as desired.

What I claim as my invention and desire to secure by Letters Patent is:

In the manufacture of cigarettes having denser tobacco portions at their ends than elsewhere, a method of producing a continuous wrapped cigarette rod in which the tobacco is denser at zones where the cigarette rod is to be cut than at other parts along its length, and of producing the said cigarettes from the said rod, which method comprises conveying an elongated tobacco filler stream which contains, substantially along its whole length, an excess of tobacco over that required for said cigarette rod, trimming the filler stream so as to remove therefrom in continuous alternation (1) less than the whole of said excess tobacco and (2) the whole of said excess tobacco, thereby leaving unremoved from the filler stream more residual tobacco per unit length of the filler stream at regularly spaced positions along the filler stream, and less residual tobacco per unit length of the filler stream between the said positions, the said positions corresponding to the said zones where the cigarette rod is to be cut, enclosing the trimmed filler stream, containing more tobacco at the said positions than therebetween, in a continuous wrapper to form the continuous cigarette rod, and cutting the wrapped cigarette rod at the said zones.
